MOLD FOR CASTING

Russell W. Taccone, Erie, Pa., assignor to Taccone Corporation, North East, Pa., a corporation of Pennsylvania

Filed May 9, 1960, Ser. No. 27,847

3 Claims. (Cl. 22—42)

This invention relates to molding machines and, more particularly, to machines for making sand molds for castings.

It has been ascertained that molds for castings are difficult to handle due to the fact that, on leaving the molding machine, they have to be placed on pattern plates in order to avoid the subsidence of the mass of sand under the effect of shocks, vibrations, the pressure of the gas at the moment of pouring the molten metal, the weight of the cast metal, etc.

It has even been noticed that it is necessary to weigh down the molds from the top of the mass of sand itself. The action of the weights which are put on the mass of sand to weigh the molds tends still more to deform the mold and, consequently, makes the pattern plate even more indispensable.

To avoid all these inconveniences, the inventor has had the idea of giving to the opposite surface of the mass of sand, to that in which the impressions are formed, the form of an arch. In this way, the vertical pressure is converted into horizontal or diagonal thrust and any point along the surface of the arch offers approximately the same resistance.

After numerous long and difficult experiments in choosing the suitable composition of the sand, its degree of humidity, the way of compressing it, the distribution of pressure on the surface of the sand, the way of exerting this pressure, and the relation between the height of the mold and the area of its surface, the inventor has constructed the molds having, on one face, the impressions and, on the other face, at least one arch capable of offering high resistance to pressures and made so that, as far as possible, any point along the surface of the arch offers approximately the same resistance.

For a given mold box, the ratio between the height of the mold and the area of the surface of the sand can be varied by positioning cross bars on the inside of the mold box in order to make several arches, if necessary.

The invention thus has as its object the provision of a new industrial product constituted by a mold for casting comprising, in combination, a mold box formed simply by an open frame for the wall of the mold and by a mass of molding sand packed in the interior of this mold box and having, on one of the open faces of the said box, at least one impression intended for receiving the molten metal and, on the other face which is also open, at least one arch capable of offering a high mechanical resistance to forces transmitted from the interior of the mold toward this face.

According to the invention, it is particularly intended that use should be made, in order to obtain molds with open faces according to the invention, of machines comprising flexible diaphragms of a large surface area arranged in such a way as to permit the desired distribution of pressures on the surface of the mass of sand and the obtaining of the required gradients of pressure in the said mass necessary to assure the formation of resistant arches according to the invention.

This construction makes it unnecessary to submit the mass of sand or other material utilized to any treatment intended to modify the composition of the mixture in order to augment its resistance.

It should be understood that when the word "sand" is

2

used, it is intended to include any molding agent which is suitable for making a mold.

It can be assumed that the very flexible, non-elastic diaphragm assures a pressure which is uniform over the whole of the surface of the arch and a slightly higher pressure than in the interior of the mass of sand due to the fact that this diaphragm does not exert any mechanical resistance at any point on its surface. This phenomenon can be compared to the construction of a pre-stressed beam. The diaphragm is only there to form a separation between the fluid (compressed air) exerting a pressure against one of its faces and the mass of sand against which the diaphragm is freely pressed.

When the mold is being made and when the compressed air is forced against the upper face of the diaphragm to pack down the mass of sand contained in the mold box, the sand tends to be a little less compressed in the zone which is close to the outside edge of the mold box than in the other zone. This is why, according to a particular embodiment of the invention, the compressed air is made to strike the interior rim of the mold box and not the complete surface in such a way that the peripheral zone of the mass of sand is the first to be submitted to the direct pressure of the compressed air, through the intermediary of the diaphragm, in order to compensate for the tendency that the sand has to be less compressed around the outside edge of the mold box.

According to the invention, the diaphragm is held by the lower edge of a part in the form of a head under which one brings the mold box in order to compress the mass of sand. In the interior of the head is also provided a deflector constituted by a horizontal plate which almost completely seals the head, except on its inside rim, where it is open, to allow the compressed air to pass.

The invention will be better understood by reading of the following description and by examination of the accompanying drawings which show, by way of non-limiting examples, several embodiments of the invention.

In the drawings:

FIG. 1 is a vertical sectional view through the middle of a mold according to the invention and of a device for packing the mass of sand in the mold box;

FIG. 2 is, to a smaller scale, a plan view of the deflector plate mounted in the device;

FIG. 3 is a plan view of a variation of the mold;

FIG. 4 is a sectional view taken on line IV—IV of FIG. 3;

FIG. 5 is a plan view of another variation of the mold;

FIG. 6 is a sectional view taken on line VI—VI of FIG. 5;

FIG. 7 is a section of a mold for casting according to the invention comprising a mold box which is open on the top and the bottom; and

FIG. 8 is a cross sectional view of two parts of the flask in assembled relation.

The mold according to the invention represented in FIG. 7 is formed, in combination, by a box 1 and a mass of sand 2 packed in the interior of the box 1. The box 1 is constituted simply by a frame which forms the wall of the mold and which is completely open toward the top and the bottom.

The mass of sand 2 has an impression 3 on the side of the bottom open face of the box 1 for receiving the molten metal. The impression 3 is formed by means of a pattern. The sand 2 also has an arch 5 on the side of the upper open face of the box 1 which is calculated to offer a high mechanical resistance to the forces transmitted from the interior of the mold toward this face, particularly under the effect of shocks, vibrations, and the pressure of the gases at the moment of pouring the molten metal as well as the weight and pressure of the cast metal.

To make the mold, the box 1 has, for example, been placed on a pattern plate 7 on which a pattern 4 is positioned as shown in FIG. 1, a convenient quantity of molding sand or any other suitable material has been deposited, and the sand has been packed down by means of a device comprising a head 8. The lower edge of the head 8 has the same contour as that of the box 1 and the edge of a flexible, non-elastic diaphragm 9 is attached thereto. The diaphragm 9 has a surface area easily large enough for being spread out against the top of the mass of sand, without ever being stretched. The edge of the diaphragm 9 is held between the edge of the head 8 and a clamping ring 11, of the same contour as that of the head 8 and of the mold box 1, and is fixed to the head 8 by screw bolts 12.

The clamping ring 11 extends inwardly all around the flask and forms a shelf for supporting the edge of the diaphragm 9 and a deflector for air. The inner edge of the diaphragm 9 is rounded to protect the diaphragm 9.

The top of the head 8 has perforations 13 through which compressed air is admitted to effect the packing down of the sand. In order that the direct pressure of the compressed air is first made to act near the wall of the box, the interior of the head is fitted with a horizontal deflector plate 14, the outside edge of which has notches 15 cut out of it to a distance of no more than twice the inward extent of the clamping ring 11. The plate 14 is welded to the inside wall of the head 8 by parts 16 formed between each successive notch. The compressed air which is admitted into the head by the perforations 13 to effect the packing down of the sand passes afterwards through the notches 15 in the deflector plate 14 and then strikes against the diaphragm 9 in the vicinity of its outside edge.

To make the mold, a convenient composition of sand or other equivalent material is chosen, with the correct degree of humidity. The desired amount of sand is then placed in the box which is positioned under the head, which has the diaphragm 9 attached to it, and compressed air is then admitted into the head. Due to the previously mentioned properties of the diaphragm 9, the air exerts an evenly distributed pressure on the mass of sand and forms, on the top surface, an arch, any point along the surface of which offers approximately an equal resistance to pressure, the mass of sand on the interior being submitted to a corresponding and equally uniform compression.

The relation between the height of the mold and the area of its surface is chosen in such a way that a sufficient thickness of sand remains between the impression 50 of the pattern and the crown of the arch.

In FIGS. 3 and 4, a variation of the mold is represented in which the box 1 is fitted, on the inside, with cross bars 18 on which the diaphragm for packing down the sand rests, in such a way as to form several arches such as indicated at 5'.

The choice of the number and of the form of the arches depends upon the form of the impressions and of their dimensions, as well as the form and the dimensions of the mold box and it is determined in such a way that a mold is obtained having all the required qualities of resistance to pressure.

Thus, for the form of the mold represented in FIGS. 5 and 6 which utilizes a circular mold box, cross bars are provided in the form of cantilevered radial ribs 21 of curvilinear profile which are supported at their roots by the inside wall of the box. The cross bars 18 of the embodiment in FIGS. 3 and 4 are supported at their two extremities by two inside opposite faces of the box.

It will be understood that the invention is in no way limited to the embodiments described and shown in the drawings and many modifications and changes may be made therein by those skilled in the art, according to the desired applications, without departing from the scope of the invention.

The embodiments of the invention in which an exclusive property or privilege is claimed are defined as follows:

1. A molding machine comprising a flask frame open at the top and bottom and supported on said molding machine, a flexible diaphragm supported on said molding machine over said flask frame, and means to direct air at high pressure onto said diaphragm at spaced positions disposed at the outer edges of said flask frame only whereby said diaphragm compresses sand near the edges thereof more than at the center, thereby forming the surface in the shape of an arch.

2. The machine recited in claim 1 wherein said means to direct air onto said diaphragm comprises a plate supported over said frame, and a clamping ring attached to said plate and surrounding the edges of said frame and underlying the edges of said diaphragm whereby said air impinging on said diaphragm is directed away from the edges of said frame.

3. The machine recited in claim 2 wherein said plate has openings around the edges thereof and overlying said clamping ring.
